UNITED STATES PATENT OFFICE

2,364,850

ROTARY DRILLING APPARATUS

Harry C. Johansen, Michigan City, Ind., assignor
to Sullivan Machinery Company, a corporation
of Massachusetts

Application December 1, 1941, Serial No. 421,123

8 Claims. (Cl. 255—22)

This invention relates to drilling apparatus, and more particularly has reference to improvements in a rotary oil well drilling apparatus of the portable type.

In rotary oil well drilling apparatus, it is desirable to maintain the top of the rotary table clear for the usual rotary drilling operations, and to provide for this it is necessary to arrange the drill feeding mechanism below the rotary table. When a conventional form of hydraulic feeding mechanism is employed upon a portable drilling apparatus, the feed cylinders, when the feeding mechanism is arranged below the rotary table, will project downwardly with their lower ends very close to the ground surface over which the apparatus travels during transport. With the feed cylinders so disposed, the same will interfere with proper transport of the apparatus particularly when traveling over rough ground, since there is danger of the feed cylinders striking obstacles, possibly resulting in injury to the apparatus; and it is therefore necessary to elevate the feeding mechanism to provide for additional road clearance before safe and rapid transport of the apparatus over rough ground surfaces is feasible. In such well drilling apparatus, it is also desirable at times to remove entirely the feeding mechanism and rotary table from the drill frame, as, for instance, during setting of well casing.

It is a primary object of the present invention to provide a portable rotary oil well drilling apparatus which not only has the top of the rotary table clear but also may have its feeding mechanism elevated during transport to provide for adequate road clearance. Another object is to provide an improved guide mounting structure for the feeding mechanism of a rotary drilling apparatus whereby the feeding mechanism may be elevated. Yet another object is to provide an improved supporting structure for the feeding mechanism of a rotary drilling apparatus. A further object is to provide a feeding mechanism and rotary table which may be readily completely removed from their supporting structure as, for instance, to enable setting of well casings. A still further object is to provide an improved drill feeding and rotating mechanism having novel arrangements and combinations of parts. How these and other objects are accomplished, and the advantageous features of the invention, will be best understood from the following detailed description wherein a preferred and illustrative embodiment is set forth, reference for the purpose

being had to the accompanying drawings, in which:

Fig. 1 is a side elevational view of a drilling apparatus in which an illustrative embodiment of the invention is incorporated.

Fig. 2 is an end elevational view of the drilling apparatus shown in Fig. 1.

Fig. 3 is an enlarged vertical sectional view, with parts in elevation, taken through the feeding mechanism and rotary table, substantially on the plane of line 3—3 of Fig. 1.

Fig. 4 is an enlarged view in longitudinal vertical section taken substantially on line 4—4 of Fig. 2.

Fig. 5 is an enlarged horizontal sectional view taken substantially on line 5—5 of Fig. 1.

Fig. 6 is an enlarged horizontal sectional view taken substantially on line 6—6 of Fig. 1.

Fig. 7 is a vertical sectional view taken on the plane of line 7—7 of Fig. 1, showing the feed pistons blocked in raised position.

Fig. 8 is a sectional view, similar to Fig. 7, showing the feed cylinders blocked in raised position.

In its illustrative construction the invention is incorporated in a rotary oil well drilling apparatus of the portable type, although it will be understood that the invention, at least from certain of its aspects, may be associated with other types of drilling apparatus.

The drilling apparatus disclosed comprises an automobile truck 1 having a platform 2 on which the drill is mounted. The drill includes a rotary mechanism 3, feeding mechanism 4, hoisting mechanism 5, a mud pump 6 and a derrick mast 7. The derrick mast is pivoted at 8 on a supporting frame structure 9 mounted on the truck platform, and is swingable in a vertical direction about its pivot from its lowered transport position shown in full lines in Fig. 1 to its raised operative position shown in dotted lines in that figure. The mast carries near its top a usual sheave 10 around which the hoisting cable 11 wound on a hoisting drum 12, may be extended, in a well known manner. Hydraulic jacks 13 are arranged at the opposite sides of the truck platform for swinging the derrick mast about its pivot. The drill may be driven from the truck engine through a suitable power take-off including shafting 14 (Fig. 5) through any appropriate connections, and herein the shafting 14 is connected through bevel gearing 15 to a transverse shaft 16 suitably journaled within the drill frame 17. Connectible by a sliding clutch 18 (Fig. 5) to this shaft 55 is a chain sprocket 19 which is connected by an

endless drive chain 28 to a sprocket 21 secured to the drive shaft 12 (Fig. 6) of the hoisting drum 12. Keyed to the shaft 18 and driven thereby is a chain sprocket 23 connected by an endless drive chain 24 to a chain sprocket 25. This chain sprocket is suitably journaled within the drill frame and has splined thereto an axially movable "clutch" shaft 26 connectible to a suitable coupling 27 secured to a shaft 28. The shaft 28 is herein arranged parallel with the shaft 18 and is likewise journaled within the drill frame. The shaft 28 has secured thereto and drives a bevel gear 29 meshing with a bevel gear 30 (Figs. 4 and 5) having its hub journaled within a cross frame 31, which is supported by the frame 2 and adapted to be raised and lowered relative to the latter as later described. Splined within the hub of the bevel gear 30 is an axially movable shaft 32 (Fig. 4) which is journaled within a vertically reciprocable crosshead frame 33 arranged above the cross frame 31. This splined shaft has a tubular casting 34 secured to the cross frame 31. The splined shaft 32 is movable vertically with the crosshead frame 33 and, due to its splined connection with the hub of the bevel gear 30, is always connected in driven relation with the bevel gear. Keyed to the upper end of the shaft 32 is a chain sprocket 35 (Fig. 4) connected by an endless drive chain 36, arranged within the crosshead frame, to a chain sprocket 37 secured to a rotary table 38. The rotary table is journaled within bearings supported within the crosshead frame 33 and has a central opening 39 in which is received a drive bushing 40. This drive bushing carries conventional slips 41 adapted to grip a conventional drill stem 42 passing centrally through the opening of the rotary table. This drill stem is attached to the usual drill rod line by which the drill bit is carried.

The feeding mechanism 4 comprises parallel feed cylinders 43, 43 arranged vertically on and carried by the cross frame 31 and containing reciprocable feed pistons 44 having their piston rods 45 extending upwardly through the top cylinder heads 46. These cylinder heads are formed integral with the cross frame 31. The piston rods 45 are secured at their upper ends, as at 47, to the opposite sides of the crosshead frame 33, so that the latter is supported by the feed pistons. Liquid under pressure may be supplied to the opposite ends of the feed cylinders 43 through suitable pipe connections 48 and 49 under the control of a usual valve mechanism (not shown) from any suitable source of liquid pressure supply. From the foregoing it is evident that when the clutch 18 is connected the hoisting drum 12 may be rotated in a direction to wind in the hoisting cable 11, and when the shiftable splined "clutch" shaft 26 is connected to the coupling 27 the rotary table 38 may be rotated to effect rotation of the drill stem 42, in the manner well understood by those skilled in the art. When liquid under pressure is supplied to one end or the other of the feed cylinders 43, the feed pistons 44 may be moved to effect vertical movement of the crosshead frame 33, and, as a result, the drill stem 42 may be moved axially with the rotary table, in an obvious manner. During the usual rotary drilling operations, the drill stem may slide axially through the table bushing while it is concurrently rapidly rotated by the table, but at times the hydraulic feed piston may be operated to control the rate of axial feed of the drill stem and may be operated to raise the drill stem with the table. The hoisting cable 11 may be attached to the

upper end of the drill stem in a well known manner, to effect raising and lowering of the stem through the rotary table, for instance during handling of the drill rod line. As the mode of operation of a rotary drilling apparatus of the type disclosed is well known to those skilled in the art, further description thereof is deemed unnecessary.

Now referring to the improved mounting structure for the feeding mechanism whereby the latter may be raised to increase the road clearance during traveling of the drilling apparatus, it will be observed that the feed cylinders 43 are slidably received in vertical bores 50 in lugs 51 integral with the drill frame 17. When the feeding mechanism is in its lowered operative position on the drill frame, the feed cylinders 43 extend downwardly beneath the rotary table with their lower ends in close adjacency to the ground surface, as shown in Figs. 1, 2 and 7, and the feed cylinders may be held rigid with respect to the drill frame by eye-bolts 52 pivoted at 53 on the drill frame and receivable in slots 54 in lateral lugs 55 integral with the cross frame 31. The eye-bolts have tightening nuts 56 threaded thereon, and these nuts when tightened rigidly clamp the feed cylinders in stationary position, with the cross frame 31 resting on the top of the drill frame. With the parts thus disposed, liquid under pressure may be supplied to the feed cylinders to move the feed pistons, thereby to effect feeding of the crosshead frame and rotary table in a vertical direction, and, as a result, the drill rod line may be raised or lowered as desired. It is accordingly evident that the drill rod line may be rotated by the table either as it is fed with the table or as it slides axially through the table. To increase road clearance during traveling of the apparatus, the eye-bolts may be released and liquid under pressure may be supplied to the lower ends of the feed cylinders to effect raising of the feed pistons to the positions shown in Fig. 7. Blocks or spacer elements 57 may then be placed between the crosshead frame 33 and the drill frame 17, in the manner shown, to hold the feed pistons in raised position. Liquid under pressure may then be supplied to the upper ends of the feed cylinders to effect movement of the latter vertically within their guide bores relative to the then stationary feed pistons, raising the cylinders and the cross frame 31 to the position shown in Fig. 8. Blocks or spacer elements 58 may then be placed between the lateral lugs 55 on the cross frame 31 and the drill frame 17 to hold the feed cylinders, frame 31, and tubular casing 34 in raised position. With the feed cylinders, etc. so elevated, the road clearance is increased so that the drilling apparatus may travel over an uneven ground surface without the danger of the cylinders striking some obstacle. If desired, suitable clamping means may be provided to hold the feed cylinders and associated parts in raised position during transport. Also, the feed cable 11 may be attached to a part of the feeding mechanism, so that the hoisting mechanism may be used to raise the feeding mechanism, instead of the hydraulic feed cylinders.

At times it is desirable to remove completely the feeding mechanism from the drill frame, for instance, during setting of well casing which is of a diameter larger than the central opening of the rotary table. Removal of the feeding mechanism from the drill frame may be accomplished simply by attaching the hoisting cable 11 to a

part of the feeding mechanism so that when the cable is wound in by the hoisting drum the entire feeding mechanism may be raised as a unit from its mounting on the drill frame. To withdraw the cylinders 43 from the lugs 51 the lower feed connections 49 would, of course, have to be removed, or the lugs must be slotted to permit passage of the connections 49. In a similar manner, the hoisting mechanism may be employed to replace the feeding mechanism on the drill frame.

As a result of this invention it will be noted that an improved rotary oil well drilling apparatus of the portable type is provided wherein the top of the rotary table is not only kept clear but also adequate road clearance is provided during traveling of the apparatus. It will also be evident that by the provision of the improved mounting structure for the feeding mechanism the latter may be arranged with its feed cylinders beneath the rotary table during the drilling operation and may be raised on its mounting structure to increase road clearance during traveling of the apparatus. It will also be noted that by the provision of the improved mounting structure for the feeding mechanism the latter may be removed as a unit from the drill frame to facilitate setting of well casing. Other objects and advantages of the invention will be clearly apparent to those skilled in the art.

While there is in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a drilling apparatus, a portable base adapted to travel over a ground surface, fluid operated drill feeding mechanism on said base including cooperating relatively reciprocable, relatively upright, feed cylinder and piston elements, means associated with one of said elements for holding the same during normal drilling operations in a relatively upright position on said base with its lower end near the ground level, means for holding the other of said elements at will in a relatively elevated upright position and against downward movement, and means for supplying fluid to said elements selectively to effect downward movement of said last mentioned element to effect drill feeding when the first mentioned element is held stationary or to effect elevation of said first mentioned element to increase the clearance beneath the same when said second mentioned element is so held stationary.

2. In a drilling apparatus, a portable base adapted to travel over a ground surface, fluid operated drill feeding mechanism on said base including cooperating relatively reciprocable, vertically disposed, feed cylinder and piston elements operative upon supply of operating fluid thereto to effect drill feed, one of said feeding elements being guided for vertical movement on said base and normally during operation of the feeding mechanism being stationary with respect to said base in a position wherein its lower end is disposed near the ground surface, releasable means for holding said normally stationary feeding element against vertical movement with respect to said base and releasable to permit free vertical movement of said element upwardly with respect

to said base, and means for holding said normally movable feeding element in raised position and against downward movement with respect to said stationary feeding element whereby upon supply of operating fluid thereto said normally stationary feeding element may be raised vertically with respect to said base to increase the clearance of its lower end with respect to the ground surface.

3. In a drilling apparatus, a portable base adapted to travel over a ground surface, fluid operated drill feeding mechanism on said base including cooperating relatively reciprocable, vertically disposed, feed cylinder and piston elements operative upon supply of operating fluid thereto to effect drill feed, one of said feeding elements being guided for vertical movement on said base and normally during operation of the feeding mechanism being stationary with respect to said base in a position wherein its lower end is disposed near the ground surface, releasable means for holding said normally stationary feeding element against vertical movement with respect to said base and releasable to permit free vertical movement of said element upwardly with respect to said base, means for holding said normally movable feeding element in raised position and against downward movement with respect to said stationary feeding element whereby upon supply of operating fluid thereto said normally stationary feeding element may be raised vertically with respect to said base to increase the clearance of its lower end with respect to the ground surface, and means for holding said normally stationary feeding element in its raised position with respect to said base during traveling of the apparatus.

4. In a drilling apparatus, a portable base adapted to travel over a ground surface, fluid operated drill feeding mechanism on said base including cooperating relatively reciprocable, vertically disposed, feed cylinder and piston elements operative upon supply of operating fluid thereto to effect drill feed, one of said feeding elements being guided for vertical movement on said base and normally during operation of the feeding mechanism being stationary with respect to said base in a position wherein its lower end is disposed near the ground surface, releasable means for holding said normally stationary feeding element against vertical movement with respect to said base and releasable to permit free vertical movement of said element upwardly with respect to said base, means for holding said normally movable feeding element in raised position and against downward movement with respect to said stationary feeding element whereby upon supply of operating fluid thereto said normally stationary feeding element may be raised vertically with respect to said base to increase the clearance of its lower end with respect to the ground surface, and means for holding said normally stationary feeding element in its raised position with respect to said base during traveling of the apparatus.

5. In a drilling apparatus, a portable base adapted to travel over a ground surface, drill rotating mechanism on said base including a drill rotating element movable vertically relative to said base, fluid operated drill feeding mechanism on said base including cooperating relatively reciprocable, vertically disposed, feed

cylinder and piston elements operative upon supply of operating fluid thereto to effect drill feed, said rotating element moving with the drill so that the latter is rotated as it is fed, and one of said feeding elements being guided for vertical movement on said base and being normally stationary on said base with its lower end disposed near the ground surface, releasable means for holding said normally stationary feeding element against movement with respect to said base and releasable to free said element for vertical movement in an upward direction, releasable means for holding said normally movable feeding element against downward movement with respect to said base to hold said element and said drill rotating element in raised position whereby upon supply of operating fluid thereto said normally stationary feeding element may be raised with respect to said base to increase the clearance of its lower end with respect to the ground surface, and releasable means for holding said normally stationary feeding element in its raised position with respect to said base.

6. In a drilling apparatus, a portable base adapted to travel over a ground surface, fluid operated drill feeding mechanism on said base including a vertical feed cylinder extending downwardly with respect to said base with its lower end disposed near the ground surface and containing a reciprocable feed piston and operative upon supply of operating medium to said cylinder to effect movement of said feed piston to feed a drill toward the work, releasable means for holding said feed cylinder in a stationary position on said base during the feeding operation and releasable to free said cylinder for vertical upward movement with respect to said base, and means for holding said feed piston in its raised position in said feed cylinder and against downward movement with respect to said base whereby upon supply of operating fluid to said cylinder the latter may be raised with respect to said base to increase the clearance of its lower end with respect to the ground surface.

7. In a drilling apparatus, a portable base adapted to travel over a ground surface, fluid operated drill feeding mechanism on said base including a vertical feed cylinder extending downwardly with respect to said base with its lower end disposed near the ground surface and con- 50

taining a reciprocable feed piston and operative upon supply of operating medium to said cylinder to effect movement of said feed piston to feed a drill toward the work, releasable means for holding said feed cylinder in a stationary position on said base during the feeding operation and releasable to free said cylinder for vertical upward movement with respect to said base, means for holding said feed piston in its raised position in said feed cylinder and against downward movement with respect to said base whereby upon supply of operating fluid to said cylinder the latter may be raised with respect to said base to increase the clearance of its lower end with respect to the ground surface, and means for holding said cylinder in its raised position and against downward movement with respect to said base during traveling of the apparatus.

8. In a drilling apparatus, a portable base adapted to travel over a ground surface, drill rotating mechanism on said base including a drill rotating element movable vertically with respect to said base, fluid operated drill feeding mechanism on said base including a vertical feed cylinder extending downwardly with its lower end disposed near the ground surface and containing a reciprocable feeding piston and operative upon supply of operating medium thereto to effect downward movement of said piston and said drill rotating element to feed a drill toward the work during drill rotation, releasable means for holding said cylinder in a stationary position on said base during the feeding operation and releasable to free said cylinder for vertical upward movement with respect to said base, means for holding said feed piston and said drill rotating element in their raised position with respect to said feed cylinder and said base and against downward movement with respect to said base whereby upon fluid supply to said cylinder the latter may be raised with respect to said base, said cylinder being movable into a position wherein the clearance of its lower end with respect to the ground surface is increased, and means for holding said cylinder in its raised position and against downward movement with respect to said base during traveling of the apparatus.
